UNITED STATES PATENT OFFICE.

EUGÈNE SCHNEIDER, OF LE CREUZOT, FRANCE.

SUBMARINE MINE.

1,229,797.

Specification of Letters Patent. Patented June 12, 1917.

Application filed February 11, 1916. Serial No. 77,709.

To all whom it may concern:

Be it known that I, EUGÈNE SCHNEIDER, a citizen of the Republic of France, residing at Le Creuzot, France, have invented a new and useful Improvement in or Relating to 5 Submarine Mines, which is fully set forth in the following specification.

Submarine mines are known which are composed of two elements (a float and the 10 mine proper) held in engagement by a suitable means, while a tensile device of suitable length extends between the float and the firing apparatus. When a mine of this type receives a shock, the float and the mine 15 proper are disengaged, with the result that these two elements are moved away from each other, so that the mine is fired when the tensile device becomes taut, that is to say, when the mine proper has moved away 20 from the float through a distance equal to the length of the tensile device.

Now the present invention has for its object to provide a particularly simple form of submarine mine of the type specified 25 hereinabove.

A main characteristic feature of the invention consists in a peculiar means of engagement between the float and the mine proper.

30 The mine proper is provided on its upper side with a suitable number of cramps; for this purpose it is formed preferably with bosses in which horizontal pins are mounted for an equal number of rollers. The mine 35 proper engages by means of these roller cramps upon lugs or bearings projecting from the underside of the float.

Owing to the inertia of the mine proper suspended in this manner, the rotary movement which is imparted to the float, provided with antennæ, by the action of a 40 powerful shock, will cause the disengagement of the two elements, and effect in the known way the firing of the mine charge by 45 the tensile device connecting the firing device to the float becoming taut.

The invention consists also in a simple apparatus for sinking the mine on the expiration of a determined length of time 50 when the mine is arranged as a floating mine.

The invention is illustrated in its application by way of example to a floating mine in the accompanying drawings wherein—

55 Figure 1 is an axial section of the mine;

Fig. 2 is a section on the line I—I of Fig. 1;

Fig. 3 is a section likewise on the line I—I of Fig. 1, but showing the positions of the engaging rollers after they have been 60 disengaged by the impact of a ship's hull.

Fig. 4 is a half section on the line II—II of Fig. 1.

Figs. 5 and 6 are diagrammatic views of a submerged mine, showing its elements respectively in the positions they occupy before impact, and after impact when the explosion is about to take place.

Fig. 7 is a diagrammatic view of a modification.

As shown, the upper portion of the box A containing the explosive charge is provided with brackets *a*, three in number for instance, in which are fixed or with which are formed integrally the pins *b* of vertical rollers B which are arranged to bear upon three corresponding bearings C fixed to the bottom of the float D. These rollers are situated at equal distances from the axis of the mine, and at 120 degrees from one another.

70 Each of the pins *b* has a recess in which there engages the rod *e* of a piston E which is impelled by a spring *e*¹ and is arranged to work in a cylinder F fixed to the bearing C. A block G of readily soluble substance, for instance, sugar, serves to keep the rod in its recess in the pin *b* so long as the mine is not submerged.

75 The upper part of the mine proper A is further provided with three other brackets *a*¹ which are situated between the first three, and which carry the pins *b*¹ of three horizontal rollers B¹ that bear upon three corresponding brackets C¹ fixed to the underside 80 of the float.

85 Inside the mine casing A which is annular in cross section, there is provided in the usual manner the percussion cap box H containing a detonator *h* fixed to the mine casing in a water-tight manner by any suitable means. Opposite the detonator, the head of the mine casing comprises a recess in which a friction fuse J is fixed which is connected by a brass wire K of determined length to 90 a cross piece *d* fixed to the float D. The brass wire is coiled in a funnel L which is provided on the head of the mine casing and which is intended to prevent the wire from 95 getting caught. The antennæ M in any suit- 100 105 110

able number are fixed to the float radially and are intended to take the impact of the colliding vessel and to transmit the same to the float.

5 The float is provided with an aperture N which is closed by a cover O screwing upon a union n for holding a soluble plug P. The melting of the latter causes the mine to sink to the bottom at the end of a 10 determined length of time if the mine has not been struck before.

The operation of the mine is as follows:—

15 Before submerging the mine (Figs. 1 and 2) the mine proper is connected to the float by means of the rollers B engaging the corresponding bearings. The safety rods e which are kept in their recesses by the soluble plugs G, prevent any untimely disengagement of the mine proper. The horizontal 20 rollers B¹ assure the centering of the whole while facilitating the rotary movement at the proper time.

25 The mine when placed in the water remains at the surface (Fig. 5). After a very short time the melting of the plugs G releases the rods e which are attached to the float and which on being impelled by their springs e¹ move out of their lodgments in the pins B. The mine is then ready for 30 operation.

35 From this instant onward, if the hull of a ship strikes the antennae of the float, the latter will rotate, while the mine proper remains stationary owing to its inertia. The bearings C will move away from the rollers B (Fig. 3) and the mine will sink and pay out the wire K that connects the fuse to the float.

40 When the wire has been paid out completely, that is to say when the mine proper has sunk to the predetermined depth, the friction part of the fuse is pulled out and the explosion takes place.

45 The soluble plug P begins to melt as soon as the mine is immersed in the water, and at the end of a determined length of time, owing to the continued melting, water enters the float and causes the mine to sink if it has not been previously struck by 50 a ship.

55 In cases where it is desired to diminish the visibility of the mine, the whole appliance (float and mine proper) may receive an additional float D¹ (Fig. 7) which should be given the shape of some commonly occurring floating body. In such a case the buoyancy of the whole appliance (main float D and mine proper A) must be negative, so that the positive buoyancy of the grand total 60 consisting of the elements A—D—D¹ is produced by the addition of the additional float D¹.

65 The mine when thus equipped occupies, when submerged, the position shown in Fig. 7, and its operation is the same as in the pre-

ceding arrangement, the main float rising to the surface as soon as it is released from the mine proper A.

The means of engagement consisting of 70 cramps and bearings (the cramps having preferably the form of rollers as hereinbefore described) may obviously be reversed, that is to say, the rollers may be attached to the underside of the float and the bearings may be carried by the mine proper. 75

Having now described my invention what I claim as new and desire to secure by Letters Patent is:—

1. In a submarine mine, in combination with the mine proper, a float, means normally maintaining said mine and float in unitary relationship but adapted to become disengaged upon relative movement of the mine and float, and means adapted to fire the mine upon separation of said mine and 85 float.

2. In a submarine mine, in combination with the mine proper, a float, means normally maintaining said mine and float in unitary relationship but adapted to become 90 disengaged upon relative rotation of the mine and float, and means adapted to fire the mine upon separation of said mine and float.

3. In a submarine mine, in combination 95 with the mine proper, a float, means on the mine and on the float adapted when engaged to hold the mine and float in unitary relationship but adapted to be disengaged by relative movement of the mine and float, and means adapted to fire the mine upon 100 separation of said mine and float.

4. In a submarine mine, in combination 105 with the mine proper, a float, means on the mine and on the float adapted when engaged to hold the mine and float in unitary relationship but adapted to be disengaged by relative rotation of the mine and float, and means adapted to fire the mine upon 110 separation of said mine and float.

5. In a submarine mine, in combination 115 with the mine proper, a float, hook-members on the mine and on the float adapted when engaged to hold the mine and float in unitary relationship but adapted to be disengaged by relative rotation of the mine and float, and means adapted to fire the mine upon separation of said mine and float.

6. In a submarine mine, in combination 120 with the mine proper, a float, hook-members on the mine and on the float adapted when engaged to hold the mine and float in unitary relationship but adapted to be disengaged by relative rotation of the mine and float, one of each pair of said hook-members 125 being provided with a roller which bears upon its opposed hook-member, and means adapted to fire the mine upon separation of said mine and float.

7. In a submarine mine, in combination 130

with the mine proper, a float, one of said elements having vertical projections provided with horizontal extensions constituting bearing surfaces, and the other of said elements having vertical projections provided with rollers movable about horizontal axes, said rollers when engaged with said bearing surfaces maintaining said elements in unitary relationship but adapted to be disengaged therefrom by relative rotation of said elements, and means adapted to fire the mine upon separation of said mine and float.

8. In a submarine mine, in combination with the mine proper, a float, means on the mine and on the float adapted when engaged to hold the mine and float in unitary relationship but adapted to be disengaged by relative movement of the mine and float, means centering said mine and float when in unitary relationship, and means adapted to fire the mine upon separation of the mine and float.

9. In a submarine mine, in combination with the mine proper, a float, means on the mine and on the float adapted when engaged to hold the mine and float in unitary relationship but adapted to be disengaged by relative movement of the mine and float, centering means for said mine and float comprising vertical bearing members on one of said elements and horizontal rollers engaging therewith on the other of said elements, and means adapted to fire the mine upon separation of the mine and float.

10. In a submarine mine, in combination with the mine proper, a float, members providing horizontal bearing surfaces on one of said elements, vertical rollers on the other of said elements, said members and rollers when engaged adapted to maintain said elements in unitary relationship but adapted to be disengaged by relative rotation of said elements, centering means for said elements comprising members providing vertical bearing surfaces on one of said elements and horizontal rollers engaged therewith on the other of said elements, and means adapted to fire the mine upon separation of said elements.

11. In a submarine mine, in combination with the mine proper, a float, means on the mine and on the float adapted when engaged to hold the mine and float in unitary relationship but adapted to be disengaged by rotation of said float relatively to said mine, means on the float to facilitate rotation of the same, and means adapted to fire the mine upon separation of said mine and float.

60 12. In a submarine mine, in combination with the mine proper, a float, means on the mine and on the float adapted when engaged to hold the mine and float in unitary relationship but adapted to be disengaged by rotation of said float relatively to said mine,

antennæ on the float to facilitate rotation of the same, and means adapted to fire the mine upon separation of said mine and float.

13. In a submarine mine, in combination with the mine proper, a float, means normally maintaining said mine and float in unitary relationship but adapted to be disengaged by relative movement of the mine and float, a lock for said means tending to move to unlocked position, and a soluble detent for said lock.

14. In a submarine mine, in combination with the mine proper, a float, means normally maintaining said mine and float in unitary relationship but adapted to be disengaged by relative movement of the mine and float, a lock for said means, a spring tending to move said lock to unlocked position, and a soluble detent for said lock.

15. In a submarine mine, in combination with the mine proper, a float, means normally maintaining said mine and float in unitary relationship but adapted to be disengaged by relative rotation of said mine and float, a lock to prevent said relative rotation tending to move to unlocked position, and a soluble detent for said lock.

16. In a submarine mine, in combination with the mine proper, a float, means normally maintaining said mine and float in unitary relationship but adapted to be disengaged by relative rotation of said mine and float, a lock to prevent said relative rotation, a spring tending to move said lock to unlocked position, and a soluble detent for said lock.

17. In a submarine mine, in combination with the mine proper, a float, hook-members on said mine and on said float adapted when engaged to maintain said mine and float in unitary relationship but adapted to be disengaged by relative rotation of the mine and float, a lock normally maintaining said hook-members in engagement but tending to move to unlocked position, and a soluble detent for said lock.

18. In a submarine mine, in combination with the mine proper, a float, members presenting horizontal bearing surfaces on one of said elements, members provided with rollers movable about horizontal axes on the other of said elements, said members adapted to maintain said elements in unitary relationship but adapted to be disengaged by relative rotation of said elements, locking pins carried by the members on one of said elements adapted to engage recesses in the members on the other of said elements, springs impelling said locking pins to unlocked position, and soluble detents for retaining said pins in locked position.

19. In a submarine mine, in combination with the mine proper, a float, means normally maintaining said mine and float in

unitary relationship, and means for firing the mine upon separation of said mine and float, said means comprising a tensile member connected to said mine and float, a funnel within which said tensile member is normally coiled, and percussion means operated by said tensile member upon becoming taut.

In testimony whereof I have signed this specification in the presence of two subscribing witnesses.
